US0D1048450S

(12) United States Design Patent (10) Patent No.: US D1,048,450 S
(45) Date of Patent:  Oct. 22, 2024

(54) MASSAGE DEVICE

(71) Applicant: TENGA Co., Ltd., Tokyo (JP)

(72) Inventor: Izumi Gemma, Tokyo (JP)

(73) Assignee: TENGA CO., LTD., Tokyo (JP)

() Term: 15 Years

(21) Appl. No.: 35/515,715

(22) Filed: Nov. 8, 2022

(80) Hague Agreement Data

Int. Filing Date: Nov. 8, 2022

Int. Reg. No.: DM/225003

Int. Reg. Date: Nov. 8, 2022

Int. Reg. Pub. Date: Dec. 2, 2022

(30) Foreign Application Priority Data

Jun. 17, 2022 (JP) 2022-013071

(51) LOC (14) Cl. 24-01

(52) U.S. Cl.

USPC D24/215
